W. J. CRAFT ET AL

AUTOMOBILE SPEED WARNING SIGNALING DEVICE

Filed April 11, 1925

Fig. 1.

UNITED STATES PATENT OFFICE.

WILLIAM JAMES CRAFT, OF LOS ANGELES, AND OTTO M. CLINTON, OF GLENDALE, CALIFORNIA.

AUTOMOBILE SPEED-WARNING SIGNALING DEVICE.

Application filed April 11, 1925. Serial No. 22,400.

This invention has reference, generally, to improvements in automobile speed warning signaling devices; and the present invention relates, more particularly, to a mechanical-electrical device adapted to be connected to automobiles, yet in no wise interfering with their starting, operation and stopping control mechanism, or speed as indicated on the speedometer. The objects of this invention are primarily, to secure an accurate electrical-mechanical device to effectively and unmistakably attract by a suitable warning note when a certain speed limit selected at will is reached.

This invention contemplates the provision of a means for performing the above object; and embodies a device that is mechanically perfect, durable in construction, and correct in principle.

The full objects of this invention, not at this time more particularly enumerated, will be clearly understood from the following detailed description thereof.

With the various objects of this invention in view, the said invention consists, primarily, in the arrangement and combinations of the devices and parts, as well as in the details of the construction of the said parts, as described in detail in the following specification, and then finally embodied in the clauses of the claim which are appended to and which form an essential part of this specification.

The invention is clearly illustrated in the accompanying drawing, in which:

Figure 1 is a diagrammatic view of the device partly in section.

Referring in detail to the drawing the numeral 1 designates a speedometer gear common to all automobiles, 2 is a pinion meshing with the said gear which in turn drives a shaft 3 revolving within the bearing 4. Mounted on the shaft 3 is a mitre gear 3' meshing with a mitre gear 8 connected by means of a recess 8' to a key 6 at one end of a drive shaft 6, the other end of the said shaft being engaged by means of a recess 6' therein and a key 13' to the speedometer cable 11; all of above with the exception of the said drive shaft 6 being common to and a part of the speedometer mechanism of all automobiles. The said mitre gear 8, drive shaft 6 as well as the male or keyed end 13 of the aforesaid speedometer cable

11 being journaled in bushings 9 and 10 supported in a case or housing 5.

The numeral 12 indicates the female connection on the end of the speedometer cable which ordinarily is engaged directly to the recessed end 8' forming part of the mitre gear 8 being the usual way of driving speedometers from the transmission or drive shaft of automobiles, the insertion of the drive shaft 6 being the means we employ to operate our device, the same in turn operating the speedometer in the usual manner as if the said shaft had not been inserted. Mounted on the said drive shaft 6 is a mitre gear 7 which meshes with a mitre gear 14, the same having a tubular hub 15 which journals in ball bearings 16 and 17. Lugs 18 on the hub 15 carry pins 19 on which are mounted governor weights 20 and 21 on the inner ends of which are fingers 22 which press against a plunger 23 which in turn presses against a ball 24 forcing the seat block 25 against a spring 41 as the said weights 20 and 21 move outwardly. The member 44 is a regulating screw for adjusting the tension on the spring 41, 43 being a protecting cap for the said screw.

A lever 28 pivoted near one of its ends has its shorter arm 27 projecting into a slot 26 in 25, the longer arm of 28 forming at its outer end 29 a point of contact as it is moved in and out, with the contacts 30 suitably mounted on an insulated base 31. A contact wire 34 passes from its connection on the lever 28 thru a flexible cable to a contact on the buzzer 36, wire leads 32 from the contacts 30 passing thru a flexible cable 42 leading from the case 5 to the contacts 33 on the control disc 40. Mounted on the said disc is a contact lever pivoted at its center, one end 38 of which is an indicator, the other end terminating into a button 39 to which is suitably attached a contact spring 38' functioning as a buss bar. A wire 35 running from the center of the control lever is connected in any suitable manner to any suitable ground on the automobile, and a similar lead from the automobile battery 37 to the buzzer 36 and the ground completes the circuit.

While a buzzer is shown in the drawing as a means for creating a warning note or signal, a horn or bell would answer just as well. The drawing further shows the indi-

cator 38 at the 0 or zero mark and the contact point 29 of the lever 28 at the 15 mile contact point so that with the device in this position the automobile can be driven at any speed without causing the buzzer or other alarming means to operate, but when the indicator 38 is set at any one of the numerals on the disc, and that particular speed is reached, the warning note is made and the 10 light 45 simultaneously caused to burn.

The device has its primary purpose to serve as a warning note when a speed greater than is desired to be made is exceeded. Speedometers have their use and as far as 15 they go, they answer their purpose. With the maze of traffic met with, however, the automobile has too many different duties to perform to constantly watch his speedometer, and this is the reason why it would seem 20 that a device as we have invented should prove itself of inestimatable value and a valuable part of any automobile.

Our device is readily attached to any automobile without changes of any kind and 25 at very little expense. The control disc and the lamp are the only parts thereof above the automobile floor, the lamp can readily be attached to the dash board and the control disc may be attached likewise or on 30 the steering wheel as might be preferred. In its operation it is exceedingly simple, the movement with the hand of the indicator 38 to the numeral on the disc indicating the speed it is desired not to reach being 35 all that is necessary; the warning sound being made and the lamp being caused to light up when the speed thus indicated is reached. Assuming that in passing thru the business district of any city, the automobile notes signs limiting his right to 40 drive at a speed no greater than 15 miles per hour, all that it would be necessary for him to do would be to move the aforesaid indicator to the numeral 15 on the disc and 45 drive on without worrying about his speedometer reading, exceeding the speed limit and possible arrest, for just as soon as this speed is reached the device unfailingly with its powerful, penetrating and unmistakable 50 warning note and the lighted lamp would attract his instant attention. It warns in plenty of time, at once, and it keeps on warning until the speed is either reduced to a speed lower than that as indicated by the 55 position of the indicator on the disc, or the indicator itself is moved to another numeral on the disc greater than the speed at which the automobile is traveling.

We are aware, that some changes may be 60 made in the general arrangements and combinations of the devices and parts, as well as in the details of the construction of the same, without departing from the scope of the present invention as set forth in the

foregoing specification, and as defined in the 65 claims which are appended thereto. Hence, we do not limit our present invention to the exact arrangements and combinations of the devices and parts as described in the said specification, nor do we confined ourself to 70 the exact details of the construction of the said parts as illustrated in the accompanying drawing.

What we do claim, however, is:—

1. In a device of the character described, 75 comprising an electrically energized mechanical structure adaptable for attachment to the speedometer actuating means of motor vehicles, a shaft, operatively connected therewith, a tubular hub, a gear on said hub and engaging with a gear mounted on said drive shaft, a plunger disposed in said hub, a pair of weight and finger members pivoted to said tubular hub, said finger members engaging said plunger, a seating block, 80 a ball positioned within said hub and engaging said seating block, said plunger engaging with said ball, a lever, said plunger, ball and seating block forming an actuating 85 means for moving said lever, and a spring member for tensioning the movement of same.

2. In a device of the character described, 90 comprising an electrically energized mechanical structure adaptable for attachment 95 to the speedometer actuating means of motor vehicles, a shaft and a tubular hub operatively engaging each other, a plunger disposed in said hub, said plunger engaging at one of its ends with a ball positioned within 100 a seating block and aforesaid tubular hub, a lever engaging said seating block, actuating weight members pivotally attached to said tubular hub, said members actuating 105 said plunger against said ball, seating block and lever, a spring adapted to bear respectively in an opposite direction, and a screw member for adjusting the same.

3. In a device of the character described 110 comprising an electrically energized mechanical structure, a shaft operatively connectable to the speedometer actuating means of motor vehicles, a tubular hub having a plunger therein disposed, means for connecting said hub to said drive shaft and for actuating said plunger, a ball engaging said plunger, and a seating block engaging said ball, a pivoted lever, disposed to engage with a speed indicating device, said lever 115 spring tensioned against said seating block, 120 and actuated by the movement of the said plunger, ball and block.

In testimony, that we claim the invention set forth above, we have hereunto set our hands this eighteenth day of March, 125 1925.

WM. JAMES CRAFT.
